UNITED STATES PATENT OFFICE.

RALSTON C. KINTZING, OF BROOKLYN, NEW YORK.

DYNAMO OR MOTOR.

SPECIFICATION forming part of Letters Patent No. 470,057, dated March 1, 1892.

Application filed October 13, 1891. Serial No. 408,621. (No model.)

To all whom it may concern:

Be it known that I, RALSTON C. KINTZING, a citizen of the United States, and a resident of Brooklyn, in the county of Kings and State 5 of New York, have invented certain new and useful Improvements in Dynamos or Motors, of which the following is a specification.

The object of my invention is to construct a cheap, simple, and efficient dynamo or motor; and it relates particularly to the arrangement of the frame-work and field, whereby the best results are produced in the simplest mechanical form. It is of the spherical type, the armature and the iron-clad casing being 15 globular in form, whereby I am enabled to make not only a most efficient motor, but it also presents exteriorly a fine appearance.

In the drawings, Figure 1 is a central vertical longitudinal section of the motor; Fig. 20 2, a central vertical cross-section, and Fig. 3 an exterior view of one end of the same.

In constructing the invention I form the casing or shell in two parts divided centrally on a horizontal plane, the lower half or hemisphere 25 A having a base B integral therewith and at each end a bracket or arm, as C D, in which the armature-shaft is journaled. The upper hemisphere E is a plain shell, and these two parts are united by means of screw-threaded 30 edges, as shown, or in any other manner—as, for instance, by having them flanged and bolted together. Centrally within these shells are screw-threaded sockets to receive the screw-threaded ends of the field-magnet cores

35 F. These field-magnets have their pole-pieces or heads G cup-shaped, the curved sockets in the ends being cut out to conform to the shape of the spherical armature. The base H of the core is designed to fit snugly against 40 the inner side of the shell. The armature-shaft I, which passes horizontally through these shells, has centrally within a spherical armature-core I', and wound thereon in any suitable manner is the insulated wire, any 45 form of winding being adapted for the purpose.

In Fig. 1 I show the shaft and armature-core covered with insulated wire, as shown at J, and connected up with the commutator- 50 plates K, and one of the field-magnets is also wound, as at L; but I have made no attempt to connect up the wires, because the manner

of connecting same forms no part of my invention.

My invention has particular reference to 55 the construction and arrangement of the iron-clad frame or shell and the manner of making and attaching the field-magnets thereto.

Both the fields and the armature may be wound as desired; but I prefer the ring type, 60 with the outer surface spherical in shape and the inner surface flat. The coils are either wound on the ring by hand or are slipped on after being wound, and the whole armature is fastened to the shaft by means of a non- 65 magnetic spider, or in any way that will prevent its resting on the shaft; or it may be composed of a hollow spherical core, over the outer surface of which is wound the wire after being insulated from the core. The field-core 70 is preferably covered with copper before being wound, and the wires may be wound directly on the core or on a spool and afterward slipped on.

By employing a spherical frame connecting 75 the field-magnets, as shown, a perfect magnetic circuit is made, eliminating magnetic leakage, and by spherical poles and armatures the lines of force are concentrated more directly upon the armature, as well as giving 80 the armature a greater surface. I also claim that I am enabled to obtain by this a more intense field, slower speed, greater solidity and efficiency, protection to the field and armature, ease of construction, and general simplicity in construction.

What I claim as new is—

1. A dynamo or motor composed of a hollow spherical shell in two parts, the lower part or hemisphere having base and bracket bearings 90 for the shaft integral therewith, the opposing field-magnets being attached to the two hemispheres, respectively, substantially as set forth.

2. A dynamo or motor composed of a hollow 95 spherical shell to constitute a frame having within the field-magnet cores removably attached to the shells, substantially as set forth.

3. A dynamo or motor having a hollow 100 spherical frame, field-magnets within said shell, having hemispherical pole-pieces, and a spherical armature-core, substantially as set forth.

4. A dynamo or motor having a frame com-

posed of two hollow hemispheres secured together, field - magnets removably attached within and provided with hemispherical pole-pieces, and a spherical armature - core, substantially as set forth.

5. The combination of two hollow hemispherical shells constituting a frame for a dynamo or motor, joined together on a horizontal plane, a base and journal-bearing arms 10 cast with the lower portion, a horizontal armature-shaft journaled in said arms, a re-

movable field-magnet vertically disposed and attached to each hemisphere within, and a spherical armature - core on said shaft, substantially as set forth.

Signed at Brooklyn, in the county of Kings and State of New York, this 23d day of May, A. D. 1891.

15 RALSTON C. KINTZING.
